[57] CLAIM

The ornamental design for the sectional livestock tank, as shown and described.

DESCRIPTION

FIG. 1 is a top perspective view of a sectional livestock tank showing my new design;

FIG. 2 is an outside elevational view thereof, all sides being identical;

FIG. 3 is a top plan view thereof;

FIG. 4 is a bottom plan view thereof;

FIG. 5 is a top perspective view thereof showing three sections of FIG. 1;

FIG. 6 is an elevational view of FIG. 5 taken from the opening and showing the sides of two of the sections; FIG. 7 is an outside elevational view of FIG. 5 taken from the opposite side of FIG. 6;

FIG. 8 is a top plan view of FIG. 5;

FIG. 9 is a bottom plan view of FIG. 5;

FIG. 10 is a top perspective view showing two sections of FIG. 1;

FIG. 11 is an enlarged outside elevational view of FIG. 10;

FIG. 12 is an enlarged elevational view of FIG. 10 showing the opposite side of FIG. 11;

FIG. 13 is an enlarged top plan view of FIG. 10;

FIG. 14 is an enlarged bottom plan view of FIG. 10;

FIG. 15 is a top perspective view showing one section of FIG. 1;

FIG. 16 is an outside elevational view of FIG. 15;

FIG. 17 is an outside elevational view of FIG. 15 showing the opposite side of FIG. 16;

FIG. 18 is another side elevational view of FIG. 15, the opposite side being a mirror image of the side shown;

FIG. 19 is a top plan view of FIG. 15; and,

FIG. 20 is a bottom plan of FIG. 15.

FIG. 1FIG. 3FIG. 2

FIG. 4

FIG. 8FIG. 6

FIG. 9FIG. 7

FIG. 10

FIG. 15FIG. 19FIG. 18FIG. 16

FIG. 17

FIG. 20
